UNITED STATES PATENT OFFICE.

ROZIER DOOR OLEA, OF INDIANAPOLIS, INDIANA.

UNDERWEAR.

1,137,630.

Specification of Letters Patent. Patented Apr. 27, 1915.

Application filed June 22, 1912. Serial No. 773,607.

To all whom it may concern:

Be it known that I, Rozier Door OLEA, a citizen of the United States, and a resident of Indianapolis, in the county of Marion and State of Indiana, have invented 5 new and Improved Underwear, of which the following is a full, clear, and exact description.

This invention relates to improvements 10 in underwear and has for an object to provide a garment having the characteristics of a union garment and form separable parts arranged end to end.

Another object of the invention is to provide 15 underwear substantially continuous throughout but separable substantially centrally, whereby there will be an upper and lower garment or part when separated.

A further object of the invention is to 20 provide separable upper and lower parts of a continuous undergarment so that part of the suit may be removed without removing the entire suit.

In carrying out the objects of the invention, the garment may be knit, woven, or manufactured in any desired manner. In completing the garment, an upper or shirt part is provided, and a lower or drawers part is provided, these parts being connected 30 by securing means, without having the various parts overlap so that the usual smooth, close-fitting effect of the union garment is presented. The connection of the parts may be varied considerably without departing 35 from the spirit of the invention, as the same may be made from connecting eyelets, clasps, or ribbons arranged through suitable perforations, or an extra section may be inserted having suitable securing means designed to 40 be secured or connected with the various parts.

A practical embodiment of the invention is represented in the accompanying drawings, forming a part of this specification in which 45 similar characters of reference indicate corresponding parts in all the views.

Figure 1 is a perspective view of an undergarment disclosing an embodiment of the invention; Fig. 2 is a section through Fig. 1 50 on the line 2--2, the same being on a slightly enlarged scale; Fig. 3 is a perspective view of an undergarment, the same showing a slightly modified form of the invention to that disclosed in Fig. 1; Fig. 4 is a section 55 through Fig. 3, approximately on the line 4--4, the same being on an enlarged scale;

Fig. 5 discloses a still further modified form of the invention; and Fig. 6 discloses a modified form of the invention involving the use of an additional part or band.

Referring to the accompanying drawings by numerals, 1 indicates the upper part or shirt part of the garment, and 2 the lower or drawers part. These parts of the garment may be formed in any desired manner with their edges having a selvage, or with a binding, as desired. When these two parts are placed together, as shown in Fig. 1, the entire garment discloses substantially a one-piece garment, though divided into two parts. The parts 1 and 2 are connected together by hooks 3, connected with part 2, engaging eyes 4 secured to part 1. Of course, the hooks and eyes could be reversed if desired, without departing from the spirit 75 of the invention, and they may, if desired, be placed upon the inside or the outside of the garment.

If desired, clasps 5, Figs. 3 and 4, could be used for securing the parts 1 and 2 together. The clasp 5 is formed with a stud 6 and a socket 7, of any desired or preferred structure, as for instance the ordinary glove fastener or clasp. One part of the clasp 5 is secured to a tab 8, and the other part is secured to part 1 of the garment, tab 8 being sewed or otherwise rigidly secured to part 2 of the garment. It will be evident that tab 8 could be provided with a button-hole and part 1 with buttons so that the tabs could be readily buttoned to part 1.

Fig. 3 discloses another form of the invention in which part 1 is provided with a plurality of substantially V-shaped extensions 12 having slots 13 arranged therein, while part 2 is provided with a plurality of substantially V-shaped extensions 14 having slots 15 formed therein, the slots 13 and 15 being in line when the projecting portions of parts 1 and 2 are interlocking. This allows 100 ribbon or tape 16 to be threaded through the various slots in order that the upper and lower part of the garment may be connected together.

Fig. 6 discloses an additional modified form of the invention in which an extra band 17 is inserted, the band 17 registering with parts 1 and 2, and is formed with securing means of any desirable kind for connection with parts 1 and 2. The securing 110 means disclosed in Fig. 6 are similar to that disclosed in Fig. 5, but it will be evident

that any of the securing means disclosed in the other figures could be used without departing from the spirit of the invention. It will also be evident that other removable connecting means could be used for connecting parts 1 and 2 together so that the same will produce a substantially one-piece garment.

If desired, duplicate rows of buttons or other fastening means could be provided on the shirt or part 1, so that the length of the united garment may be changed, that is, lengthened or shortened as desired by using either set of buttons or fastening members.

Having thus described my invention I claim as new and desire to secure by Letters Patent:—

1. In a union garment structure of the class described, an upper part, a lower part

having the upper edge thereof registering 20 with the lower end of the upper part, and means for connecting said parts together end to end.

2. In a union garment structure of the class described, a shirt structure, a pants 25 structure, said pants structure being arranged end to end with said shirt structure, the upper edge of the pants contacting with the lower edge of the shirt and hook and eye connecting means connecting said shirt 30 structure and said pants structure together.

In testimony whereof I have signed my name to this specification in the presence of two subscribing witnesses.

ROZIER DORR OILAR.
